UNITED STATES PATENT OFFICE.

THEODORE FREIBERG, OF PRESCOTT, ARIZONA.

ORE CRUSHER.

Application filed July 12, 1926. Serial No. 121,863.

My invention relates to ore crushers in general and particularly to a mill for grinding or pulverizing quartz ore containing gold and one of the principal objects of my invention resides in a very simple, highly practical and efficient mill which may be easily operated and at a very low cost of maintenance. The scope of my invention extends to whatever constructions may be defined by or included within the terms or language of the appended claims.

In the drawing, Figure 1 is a top plan view of my improved ore crusher.

Figure 2 is a side elevation thereof.

Figure 3 is a longitudinal sectional view taken on the line 3—3 of Figure 1 and looking in the direction of the arrows, and

Figure 4 is a transverse sectional view taken on the line 4—4 of Figure 3.

My invention in the form or embodiment shown in the drawing and briefly described comprises a trough 10 substantially U-shaped in cross section which may be formed of a pair of side plates 11 and 12 and a bottom

13. Suitable angle irons 14 are riveted to the lower ends of the side plates 11 and 12 and the bottom 13 in the usual manner for adding rigidity to the trough shaped member 10. Angle members 15 similar in design

20 to the angle irons 14 are riveted to the outer sides of the side plates 11 and 12 near the upper ends thereof as is clearly indicated in Figures 2 and 4. The bottom 13 is preferably inclined at an angle substantially as shown in Figure 3 and is braced by suitable T irons or the bottom may be set in concrete or cement foundation.

25 A pair of journal bearings 16 are bolted or otherwise secured to the upper edges of the angle bars 15 near the ends thereof for the purpose of receiving a horizontally extending crank shaft 17. A fly-wheel 18 is keyed to one end of the shaft 17 to which a belt, not shown, may be applied for operating the mill. One end of the riding beam 19 is provided with a bearing portion 20 which is adapted to fit the crank portion 21 of the shaft 17 whereas the opposite end of the riding beam 19 is provided at its lower

30 surface with a shoe 22 which is rigidly secured to the riding beam 19 by means of bolts and nuts 23. A die 24 is firmly held upon the upper surface of the inclined bottom 13 and so arranged as to be in contact with the shoe 22 at all times regardless of the relative position between the shoe and

the die. The die 24, which is preferably constructed of a hardened steel, is provided on its upper surface with downwardly extending tapered or chamfered portion 25. 60 The beveled portion 25 preferably extends about midway the entire length of the die 24. A transversely extending brace member 26 is preferably riveted across the inner side of the trough 10 and is secured to the plates 11 65 and 12 and the bottom 13.

An opening 27 is formed in the approximate center of the brace member 26 preferably near the upper end thereof for a purpose to be hereinafter described.

70 A pair of channel members 28 are riveted to the inner sides of the plates 11 and 12 and extend from the bottom 13 to the upper edge of the trough 10. A screen 29 of a relatively fine mesh extends across the lowered end of the trough 10 and is slidably mounted within the channel members 28 as is clearly indicated in Figures 1 and 3 of the accompanying drawing. The screen 29 is securely held in place by means of a pair of 75 bars 30 which are snugly fitted between the channel members 28 and the adjacent faces of the ends of the screen 29. In this manner the bars 30 may be readily withdrawn from the channel members 28 so that the screen 29 80 may be easily removed as for cleaning or replacement. A metallic strip 31 is riveted across the lower end of the trough 10 and extends from a point below the bottom 13 to approximately midway the height thereof.

85 The die 24 is firmly held in its proper position by means of a pair of transversely extending wooden strips or bars 32 and 33 and a pair of longitudinally extending wooden bars 34. The bar 32 is firmly held between 90 the lower or chamfered edge of the die 24 and the adjacent side of the channel members 28 whereas the bar 33 is securely wedged between the upper end of the die 24 and the brace member 26. To prevent the die 24 95 from moving sidewise the wooden bars 34 are arranged to fit between the sides of the die 24 and the inside of the trough 10 between the plates 11 and 12.

100 A pair of bars 35 are pivoted at their lower ends to a transversely extending bar 36 which extends below the plate 13 and secured thereto. Trunnions 37 are formed on the outer ends of the bar 36 for pivotally mounting the bars 35 and are provided with 105 openings for receiving the usual cotter pins. A cross-bar 38 is provided with openings

near the outer ends which are adapted to align with and freely slide upon the upper portions of the bars 35.

A brace member 39 is securely fastened to the cross-bar 38 intermediate the ends thereof and is extended downwardly for the purpose of being securely fastened to the riding beam 19 as indicated at 40. Guide blocks 41 are provided with suitable openings so that they may freely move with respect to the bars 35 and are adapted to rest upon the upper and rounded ends of the cross-bar 38 as clearly shown in Figure 2. Coil springs 42 are mounted between the upper ends of the guide blocks 41 and below suitable washers and nuts which are located near the extreme upper ends of the bars 35 for the purpose of varying the resilient pressure that is to be exerted between the shoe 22 and the die 24.

A hopper 43 is secured to the outer side of the plate 12 into which an opening 44 is formed for the purpose of readily feeding ore into the inside of the trough 10. The opening 44 is of course so positioned as to direct the flowing particles of gold-bearing ore upon the die 24 so that it may slide downwardly between the die 24 and the shoe 22. With particular reference to Figure 3 it will be now readily seen that as the ore is ground or pulverized between the coating surfaces of the die 24 and the shoe 22 that the water which flows through the opening 27 of the cross member 26 will cause this pulverized quartz and ore to flow downwardly into the lowermost portion of the trough 10. This pulp and the water will of course splash up against the screen 29, is forced through and on to amalgamated copper plates in the usual manner at which point the gold ore is deposited. With this

novel arrangement of the die and shoe together with the operating mechanism therefore the ore is reduced to the pulp by a double movement of the shoe.

45

I claim:

1. An ore crusher comprising a trough having an inclined bottom, a die block mounted at the lower end of the inclined bottom, the upper surface of the die being beveled, a shoe, mounted to reciprocate upon the upper surfaces of said die block, means for feeding ore to be crushed upon the die block, a screen located across the lowermost end of said trough and means for causing the reciprocation of said shoe with respect to the die block.

50

2. An ore crusher comprising a trough having an inclined bottom, a stationary die block mounted near the lower end of the inclined bottom, the upper surface thereof being tapered, a shoe mounted to reciprocate alternately upon each of the upper surfaces of the die block, means for varying the tension of said shoe upon the die block and means for causing the reciprocation of the shoe.

55

3. An ore crusher comprising a trough having an inclined bottom, a stationary die block mounted near the lower end of the inclined bottom, the upper surface thereof being tapered, a shoe mounted to reciprocate alternately upon each of the upper surfaces of the die block, means for varying the tension of said shoe upon the die block, a trough adapted to feed the ore upon the die block, and a brace extending transversely across the inside of said trough and having an opening therein for permitting water to flow upon said die block.
